UNITED STATES PATENT OFFICE.

GOTTLÖB BINDER, OF ROCHESTER, NEW YORK, ASSIGNOR TO AMERICAN LAUNDRY MACHINERY COMPANY, OF CINCINNATI, OHIO, A CORPORATION OF OHIO.

DYING APPARATUS.

1,136,645.

Specification of Letters Patent. Patented Apr. 20, 1915.

Application filed January 21, 1914. Serial No. 813,403.

To all whom it may concern:

Be it known that I, GOTTLÖB BINDER, of Rochester, in the county of Monroe and State of New York, have invented certain new and useful Improvements in Drying Apparatus; and I do hereby declare the following to be a full, clear, and exact description of the same, reference being had to the accompanying drawings, forming a part of this specification, and to the reference-numerals marked thereon.

My invention has for its object to provide an improved construction for drying apparatus, of the general type embodying a rotary reticulate cylinder for containing the material or articles to be dried, and a heating means together with a fan, blower or other current producing medium for carrying air first into intimate relation with the heating means and thereafter through the drying cylinder or tumbler, and one of the chief purposes of my improvement is to afford a simple construction in which the different parts are readily accessible.

Another object of the invention resides in reducing the cost of operation of the machine by making a more advantageous use of the heating means, that is to say, by utilizing to the maximum extent the heated air before it is discharged from the machine. In this manner the efficiency of the apparatus is considerably increased and the cost of operation is greatly diminished by lessening the required amount of heating medium for a given amount of work performed.

To these and other ends the invention consists in certain improvements and combinations of parts all as will be hereinafter more fully described, the novel features being pointed out in the claims at the end of the specification.

In the drawings: Figure 1 is a view in end elevation of a machine embodying a preferred arrangement of my invention; Fig. 2 is an end elevation looking in the opposite direction; Fig. 3 is a view in front elevation, with parts in section; Fig. 4 is a transverse vertical sectional view, and Fig. 5 is a sectional view on the line 5^a—5^a of Fig. 4.

Similar reference characters throughout the several figures indicate the same parts.

My invention is susceptible of various applications, and in the present embodiment, I have shown it as applied to a machine for drying articles of clothing for laundry use,

and according to a preferred arrangement, A designates a casing which may be of any suitable form and is provided interiorly with the drying chamber B within which is contained the rotatable cylinder or tumbler 60 C mounted in suitable bearings at the ends of the casing and adapted to be operated in any convenient manner.

Arranged at the rear part of the casing is a heating chamber D within which are arranged a series of heating coils E adapted to be supplied with steam or other heating medium. The heating chamber is extended upwardly toward the top of the casing forming a passage F which communicates with 70 the opening G leading into the heating chamber, and thus carries the heated air to the top of the tumbler, whence it is discharged downwardly through the articles to be dried in the manner which will presently 75 be made clear.

The air is circulated through the heating chamber and drying chamber by a suitable circulating device, which preferably consists of a force fan or pressure blower H arranged beneath the drying chamber at the forward part of the casing and acting to draw in a supply of fresh air continually and discharge it rearwardly through the outlet I from which it passes into the heating chamber and upwardly to the top of the drying chamber, and then down through the tumbler. The fresh air supply may be obtained in any convenient manner and in the present arrangement, there are provided 80 a series of openings J arranged in the hinged door K which is provided at the lower part of the casing to permit access within that portion thereof.

L designates a screening chamber within which is arranged one or more screening elements. In the present instance, I employ two screens, indicated at L² and L³ respectively and arranged at an angle to the perpendicular as shown in Fig. 4. Disposed 100 between the screening chamber and the heating chamber is an exit chamber M which is separated from the heating chamber by a wall N having a comparatively wide opening Q at the bottom thereof, and preferably coextensive lengthwise with the separating wall. The upper portion of the exit chamber N is separated from the screening chamber by a wall P which is provided with a comparatively narrow opening Q establishing com- 110

munication between the screening chamber and the exit chamber when the parts are in normal or working position as shown in Fig. 4.

- 5 R designates a door which is hinged to the casing and may be opened to empty and recharge the tumbler, and when the door is opened, it is desirable to provide means for preventing an outrush of heated air into the 10 face of the operator. To this end, I provide means for shutting off communication between the air circulating device and the heating chamber when desirable, which means preferably consists of a gate or door 15 S fixed upon a rock shaft S', and adapted to be moved from the normal operative position shown in full lines in Fig. 4, to the position shown in dotted lines, so as to close the opening O. In order to accomplish the 20 operation of the door S, the rock shaft S' is provided with an arm S² to which is pivoted a lever S³ movable in a guide S⁴, from the position shown in full lines in Fig. 1 to the position shown in dotted lines. 25 The lever S³ carries a suitable handle and can be readily moved to either position, its weight being sufficient to hold the rock shaft in either extreme position after it is once operated. With this construction, when the 30 operator desires to open the door R, he first operates the lever S³ to remove the door S downwardly until it closes the opening O, so that further circulation into the heating chamber is prevented, and when the door R 35 is opened under these conditions, there is practically no circulation through the drying chamber, and hence no tendency for the heated contents to rush outwardly into the face of the operator.
- 40 T designates the exhaust, or outlet to the atmosphere, for the more heavily moisture laden air, the same being arranged at one end of the exit chamber M. With the parts in the normal position appearing in Fig. 4, 45 air is taken in at the openings J and carried into the ends of the fans H, of which there are preferably two, in the manner shown in Fig. 3, and discharged through the openings I into the screening chamber, where it passes 50 through the screens L² and L³, removing all lint and dust before issuing into the heating chamber. The air is then forced upwardly to the top of the heating chamber, thence downwardly through the drying chamber and tumbler, and again over the same course. A portion of the heated air passes 55 into the exit chamber through the opening Q and is discharged to the atmosphere at T, and the openings Q and O are so proportioned 60 that the major portion of the heated air is kept in a continuous circulation while only a small portion is discharged through the exit chamber, its place to be taken by the fresh air that is drawn in through the openings J. The screening chamber L is pro-

vided at one end with a door L⁴, to permit access to the inside, and the screens are removable to permit readily cleaning them, as well as the chamber, to free the latter of the lint which collects rapidly.

With the herein described arrangement, I provide a machine of greatly increased efficiency, owing to the fact that the heated air is used until it is thoroughly saturated with moisture and is then discharged a little 70 at a time while the larger part of the heated air circulates over and over, and I have found that by the use of such an arrangement, I am able to maintain the desired heating temperature by using less steam or other 75 heating medium in the heating chamber, and at the same time to complete the drying operation in a smaller space of time.

I claim as my invention:

1. In a drying apparatus, the combination 85 with a casing, of a drying chamber, a heating chamber arranged in the rear of the casing, an air circulating device beneath the drying chamber at the front of the casing, and a screening chamber disposed between the air circulating device and the heating chamber at the bottom of the casing and communicating with the heating chamber.

2. In a drying apparatus, the combination 95 with a casing, of a drying chamber, a heating chamber arranged at the rear of the casing, an air circulating device beneath the drying chamber at the front of the casing, a screening chamber having communication 100 with the atmosphere and with the heating chamber, and a gate or door adapted to cut off communication between the heating chamber and screening chamber.

3. In a drying apparatus, the combination 105 with a casing, of a drying chamber, a heating chamber arranged at the rear of the casing and separated by a wall extending longitudinally throughout the casing, said wall having an opening therein, a gate or door 110 movable to open or close said opening, an air circulating device beneath the drying chamber at the front of the casing and a screening chamber between the air circulating device and the heating chamber.

4. In a drying apparatus, the combination 115 with a casing having an air inlet opening, of a drying chamber, a heating chamber arranged in the rear of the casing, an air circulating device beneath the drying 120 chamber, a screening chamber in rear of the circulating device, and an exit chamber between the screening chamber and the heating chamber.

5. In a drying apparatus, the combination 125 with a casing having an air inlet opening, a drying chamber, a heating chamber arranged at the rear of the casing, an air circulating device beneath the drying chamber, a screening chamber in rear of the cir- 130

culating device, and an exit chamber between the screening chamber and the heating chamber, the wall between the heating chamber and exit chamber having an opening therein, and an adjustable door coöperating with said opening.

6. In a drying apparatus, the combination with a casing, of a drying chamber, a heating chamber arranged at the rear of 10 the casing, an air circulating device disposed beneath the drying chamber at the forward part of the casing, an exit chamber at the bottom of the casing immediately in front of the heating chamber, the wall 15 between the last mentioned chambers having an opening therein, a screening chamber in front of the exit chamber and separated from the upper part of the exit chamber by a wall having a comparatively narrow opening 20 therein, and a movable gate or door adapted in one position to cut off the upper part of the exit chamber from the lower part, and in its other position to cut off communication between the exit chamber 25 and the heating chamber.

7. In a drying apparatus, the combination with a casing, of a drying chamber, a heating chamber arranged at the rear of the casing, an air circulating device disposed 30 beneath the drying chamber at the forward part of the casing, and a screening chamber between the circulating device and the heating chamber, said screening chamber communicating with the atmosphere by a com- 35 paratively narrow opening and with the heating chamber by a comparatively wide opening.

8. In a drying apparatus, the combination with a casing, of a drying chamber, a 40 heating chamber, an air circulating device, and a screening chamber arranged between the air circulating device and the heating chamber, said screening chamber communicating with the atmosphere by a com- 45 paratively narrow opening and with the heating chamber by a comparatively wide opening.

9. In a drying apparatus, the combination with a casing, of a drying chamber, a heating chamber arranged at the rear of 50 the casing, an air circulating device beneath the drying chamber and a screening chamber disposed at the lower portion of the casing between the drying chamber and the heating chamber and communicating by 55 a comparatively small opening with the atmosphere.

10. In a drying apparatus, the combina-

tion with a casing, of a drying chamber, a heating chamber arranged at the rear of the casing, an air circulating device beneath the 60 drying chamber and a screening chamber having communication with the atmosphere by a comparatively small opening and disposed between the drying chamber and the heating chamber.

11. In a drying apparatus, the combination with a casing having an air inlet opening, of a drying chamber, a heating chamber arranged at the rear of the casing, an air circulating device between the drying 70 chamber and heating chamber, and a screening chamber having communication with the atmosphere by a comparatively small opening.

12. In a drying apparatus, the combination with a casing, of a drying chamber and heating chamber arranged at the rear of the casing, an air circulating device disposed between the drying chamber and the heating chamber, a screening chamber arranged 80 in the path of the heated air as it passes from the drying chamber to the heating chamber, the casing having a comparatively large air inlet opening, and the screening chamber communicating with the atmos- 85 phere by a comparatively small opening.

13. In a drying apparatus, the combination with a casing, of a drying chamber, a rotary tumbler disposed in the drying chamber, a heating chamber arranged at the rear 90 of the casing, an air circulating device between the drying chamber and heating chamber, a screening chamber disposed between the drying chamber and heating chamber, and communicating with the atmos- 95 phere by a comparatively small opening, and a screening member arranged in the screening chamber acting to retain the screened particles within the screening chamber.

14. In a drying apparatus, the combination with a casing, of a drying chamber and heating chamber, an air circulating device, a screening member in the path of the heated air as it passes from the drying chamber to the heating chamber, a comparatively 100 large air inlet leading to the heating chamber and a comparatively small air outlet having communication with the air as it passes from the drying chamber to the heating chamber.
